US00D920287S

(12) **United States Design Patent** (10) **Patent No.:** **US D920,287 S**
(45) **Date of Patent:** **** May 25, 2021**

(54) **SET OF PRENATAL EARBUD ADAPTERS**

(71) Applicant: **MBRIO Technologies LLC**, Cleveland, OH (US)

(72) Inventors: **Jonathan Klinger**, Cleveland, OH (US); **Julianne Hope Leibsohn**, Cleveland, OH (US)

(73) Assignee: **MBRIO Technologies LLC**, Cleveland, OH (US)

(**) Term: **15 Years**

(21) Appl. No.: **29/690,362**

(22) Filed: **May 7, 2019**

(51) LOC (13) Cl. **14-01**

(52) U.S. Cl.

USPC **D14/223; D14/224.1**

(58) **Field of Classification Search**

(57) **CLAIM**

The ornamental design for set of prenatal earbud adapters, as shown and described.

DESCRIPTION

FIG. 1 is a perspective front view of a first embodiment of a set of prenatal earbud adapters illustrating left and right adapters.

FIG. 2 is a perspective rear view of one adapter thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a perspective view of the set of prenatal earbud adapters thereof.

FIG. 10 is a perspective view of a second embodiment of a set of prenatal earbud adapters illustrating a single adapter that can be used as either a left or right adapter.

FIG. 11 is a perspective rear view of FIG. 10 thereof.

FIG. 12 is a front view thereof.

FIG. 13 is a rear view thereof.

FIG. 14 is a right side view thereof.

FIG. 15 is a left side view thereof.

FIG. 16 is a top view thereof.

FIG. 17 is a bottom view thereof; and,

FIG. 18 is a perspective view of the set of prenatal earbud adapters thereof.

The broken lines depict environment that forms no part of the claimed design.

1 Claim, 10 Drawing Sheets
